UNITED STATES PATENT OFFICE.

RIJKENT LAST, OF ENKHUIZEN, NETHERLANDS.

MACHINE FOR RAMMING OVAL CONCRETE PIPES.

1,410,021.

Specification of Letters Patent. Patented Mar. 21, 1922.

Application filed July 12, 1921. Serial No. 484,176.

To all whom it may concern:

Be it known that I, RIJKENT LAST, manufacturer, a subject of the Queen of the Netherlands, residing at Enkhuizen, in the 5 Province of North Holland, Kingdom of the Netherlands, have invented certain new and useful Improvements in or Relating to Machines for Ramming Oval Concrete Pipes, of which the following is a specification.

This invention relates to a machine for ramming oval concrete pipes with a rotating ramming mould and with a rammer which is moved up and down by a crank and 15 which is guided in a block movable to and fro in a horizontal direction. The movement of the block is at the same time derived from a templet, which is rotated by the main shaft at the same angular velocity 20 and in the same direction as the ramming mould which is carried by a table adapted to be driven by a shaft.

The usual egg-shaped concrete pipes do not however possess the same thickness of 25 wall all over, but are provided at the bottom with a flat foot, in such a manner, that although the internal periphery of the pipe is egg-shaped, the external periphery has two projecting angles.

In the hitherto known machines for ramming concrete pipes, in which the shape of the templet which moves the rammer block corresponds to the internal periphery of the pipe, the disadvantage arises that the said 35 angles are not rammed, so that they easily break off when the pipe is removed from the machine. If however the templet be given the shape of the external periphery of the pipe, the strip of material next the 40 internal periphery at the lower part of the pipe is not rammed, so that breakage at this point is to be feared.

The object of this invention is therefore to avoid this disadvantage, which object is attained by making the device (i. e. the templet) which moves the rammer block to and fro, of two parts which correspond in shape with the internal and external peripheries respectively of the article which is to be 50 produced and by providing means which compel the rammer block to alternately follow first one and then the other part of the said device.

The accompanying drawings show an example of a constructional form of the subject matter of the invention.

Figure 1 shows the same in plan.

Figure 2 is an elevation and

Figure 3 shows a detail.

As in the known machines of this kind 60 the block which guides the rammer is movable in a horizontal direction on the frame of the machine and is provided with roller 1 which is constantly held in contact with the periphery of a templet 3 by the counter-weight 2. This templet consists of two parts 65 fixed upon each other and one of which is of the shape of the internal periphery and the other of that of the external periphery of the article to be produced. The side faces 70 of the parts have however at least one common generatrix. The templet 3 is movable by means of a sleeve 4 on a vertical shaft 5 but cannot rotate relatively to the shaft. This shaft is rotated by the main shaft at 75 the same angular velocity and in the same direction as the ramming mould.

A lever 6 consisting of two bars is pivotally connected to the sleeve 4 and can be rocked about horizontal pins 7 fixed on the 80 frame of the machine.

The free end of the lever 6 carries an adjustable counter weight 8, while between the two bars of the double lever 6 is mounted a rotating roller 9, which is continually held 85 in contact with the periphery of a cam disc 10 (Fig. 3), under the action of the weight 8 that controls the templet 3 and the sleeve 4. The disc 10 is fixed on the horizontal shaft 13 which is driven by bevel wheels off 90 the main shaft 5, the ratio of transmission being such that the number of revolutions made by the disc 10 is only half as great as those of the templet 3. The disc 10 is so shaped that each time the common generatrix 95 is situated opposite the roller 1, the templet 3 is raised by the action of the weight 8, respectively is lowered by reason of the roller 9 being raised when it passes from the portion 11 of the disc 10, which has the 100 smallest radius, to the portion 12 having the largest radius. Assuming that in Fig. 1 the roller 1 is in contact with the upper part of the templet 3, it will move during a revolution of the rammer mould and therefore of 105 the templet along the upper edge thereof and consequently the rammer will follow the internal periphery of the ramming-mould. During this movement the roller 9 is in contact with the portion 12 of the disc 10. After 110 the termination of this revolution, that is to say, when the same point on the templet is

again opposite the roller 1, the roller 9 passes to the portion 11 of the disc, so that the lever 6 rocks under the action of the weight 8 and the templet is moved upwards.

5 The roller 1 now lies on the lower part of the templet and must during the next rotation follow the periphery of this part so that the rammer moves along the external periphery of the ramming mould. At the 10 end of the second revolution the roller 9 and consequently the lever 6 will be raised by the portion 12 of the disc 10 and the templet is lowered again. The parts are then situated in the original position again.

15 It will be seen from the above description that during the working of the machine the rammer alternately follows the internal and external peripheries of the ramming mould, so that the whole of the materials is sufficiently rammed in order to produce a satisfactory product.

What I claim is:

1. In a machine for ramming concrete pipes, a ramming block, a guide for the 25 block comprising members corresponding in shape respectively to the internal and external peripheries of the pipe, and means for causing the block to alternately engage and follow said members.

30 2. In a machine for ramming concrete pipes, a ramming block, a templet therefor consisting of superposed members one of which corresponds in shape to the internal periphery of the pipe and the other to the 35 external periphery of the pipe being rammed, and means for causing the block to alternately engage and follow said members.

3. In a machine for ramming concrete pipes, a ramming block, a templet therefor 40 comprising superposed guide members, and means for moving said templet to cause the guide members to alternately control the movement of the block.

4. In a machine for ramming concrete 45 pipes, a ramming block, a roller carried thereby, a templet having superposed guide surfaces adapted to be engaged by the roller, and means for raising and lowering the templet to cause the roller to alternately engage 50 said guide surfaces.

5. In a machine for ramming concrete pipes, a ramming block, a guide therefor 55 comprising superposed members corresponding in shape respectively to the internal and external peripheries of the pipe being rammed, parts of the side faces of said members being flush with each other, and means for causing the block to alternately engage and follow said members.

6. In a machine for ramming concrete pipes, a ramming block, a guide therefor 60 comprising members corresponding in shape respectively to the internal and external peripheries of the pipe being rammed, a rotatable shaft on which said guide is mounted, a lever pivotally connected to said guide, and a cam for actuating said lever to move the guide in relation to the block.

In testimony whereof, I affix my signature. 70

RIJKENT LAST.
